UNITED STATES PATENT OFFICE.

ERNEST KARL, OF LITCHFIELD, CONNECTICUT.

ADJUSTABLE CHASE AND LOCKUP FOR PRINTING, CUTTING, AND CREEASING PRESSES.

1,353,758.

Specification of Letters Patent. Patented Sept. 21, 1920.

Application filed March 9, 1920. Serial No. 364,505.

To all whom it may concern:

Be it known that I, ERNEST KARL, a citizen of the United States, and a resident of Litchfield, in the county of Litchfield and State of Connecticut, have invented a new and Improved Adjustable Chase and Lockup for Printing, Cutting, and Creasing Presses, of which the following is a full, clear, and exact description.

This invention relates to improvements in adjustable chases and lock-ups for printing, cutting and creasing presses, an object of the invention being to provide a device of the character stated, which will securely clamp the plate and which is capable of a wide range of adjustment.

A further object is to improve upon the construction illustrated and described in my application for patent filed October 26, 1918, and given Serial No. 259858.

With these and other objects in view the invention consists in certain novel features of construction, and combinations and arrangements of parts, as will be more fully hereinafter described and pointed out in the claims.

In the accompanying drawings

Figure 1 is a view in front elevation illustrating my improvements;

Fig. 2 is a view in vertical section on the line 2—2 of Fig. 1;

Fig. 3 is a view in horizontal section on the line 3—3 of Fig. 1;

Fig. 4 is an enlarged fragmentary section on the line 4—4 of Fig. 1;

Fig. 5 illustrates in perspective the junction of one of the uprights with the upper horizontal bar of the outer chase; and

Fig. 6 is a view in elevation of one of the horizontal bars showing in full lines the normal curvature of the bar and in dotted lines the straight position the bar assumes when pressure is applied on the ends when the bar is in place.

1 and 2 represent the upper and lower horizontal bars of the outer chase A which are connected at their ends by vertical bars 3 and 4, the latter provided with curved supports or runners 5 constituting inking roller carriers.

6 and 7 represent vertical adjustable standards in the chase A which are connected by horizontal upper and lower bars 8 and 9 so that said bars 6, 7, 8 and 9 constitute a clamp or frame to lock-up the plate, type, or other similar devices. The upper ends

of the bars or uprights 6 and 7 are beveled or rabbeted as shown at 10, and engage the correspondingly shaped inner face of the bar 1 as illustrated at 11, so that a wedging action is had when the inner chase is inserted in the outer chase.

The bar 6 is provided at one end with a beveled tongue 12, which is adapted to fit into any of a series of similarly shaped recesses 13 in the bar 1 to positively hold the bar 6 against movement longitudinally of the chase A, but permit this bar to be variously positioned in accordance with the use of the device.

The vertical bars or uprights 6 and 7 are provided at their outer faces adjacent one end with notched enlargements 14, and notched blocks 15 are located against said bars or uprights adjacent their other ends on the same sides of the bars as are the enlargements 14. The blocks 15 and the enlargements 14 are connected by turnbuckles 16, which permit the adjustment of the blocks 15 toward or away from the enlargements 14. The internally screw threaded sleeves of the turnbuckles are made integral with the enlargements 14 and blocks 15 respectively, and the oppositely screw threaded adjustable member of the turnbuckle 16 is made with a head 18 which is adapted to be turned to adjust the blocks relative to the enlargements, as it will be readily understood.

The bars or uprights 6 and 7 are longitudinally slotted, as shown at 19, and in order to provide these slots, the bars or uprights 6 and 7 are made up of a number of parts rigidly secured together, but may, of course, be variously made without departing from the invention.

The upper bar 8 is provided at its upper edge with notches 20, and stays 21 extend through the recessed ends 22 of the bar 8 and through the slots 19 of the bars or uprights 6 and 7 and are provided at their ends with transverse pins 23 and 24 respectively. The pins 23 engage in the notches 20 of the bar 8 and the pins 24 engage in any of the series of notches of the blocks 15.

Stays 25, corresponding to the stays 21, connect the lower bar 9 with the notched enlargements 14 and these stays 25 have pins 26 engaging in notches 27 in the lower face of the bar 9 and have pins 28 in their other ends engaging the notched enlargements 14. The stays are of general compound curva-

ture which makes it possible to conform to the varying size of the rectangular frame formed by the bars 6, 7, 8 and 9, and these stays with their pins can be readily located 5 in the notches around the plate or type to fit the same. After the parts are properly fitted, the turnbuckles 16 are adjusted to draw the blocks 15 toward the enlargements 14 and securely lock-up the plate or type.

10 The horizontal bars 8 and 9 are bowed or curved longitudinally, this curvature being relatively slight, but sufficient to give a spring pressure at the center of the bars against the plate or type when the bars are 15 in position and the pressure on the ends of the bars will, of course, straighten the bars, yet the pressure at the center thereof is always maintained.

10 It will be noted that with my improved mechanism, the operation can be quickly performed and the device will securely 20 clamp the plate or type set up, and by reason of the structure above described, while the parts are adjustable, they are rigidly 25 fixed when once clamped in position.

Furthermore, it will be noted that I dispense altogether with locking screws at upper end of the uprights as in the application above referred to.

30 I have not attempted to describe the use of my improved device as illustrated in connection with a printing press as its use is identical with the use of the device in my application above described.

35 Various slight changes might be made in the general form and arrangement of parts described without departing from the invention, and hence I do not limit myself to the precise details set forth, but consider 40 myself at liberty to make such changes and alterations as fairly fall within the spirit and scope of the appended claims.

I claim:

1. A device of the character described, 45 comprising an outer chase, vertical bars adjustably supported in the outer chase, horizontal bars between the vertical bars, fixed notched extensions on the outer faces of the vertical bars adjacent one end of the latter, notched blocks on the outer faces of said 50 vertical bars adjacent their other ends, turnbuckles connecting said blocks and extensions, and stays connecting the notched extensions with the lower bar and the notched blocks with the upper bar.

2. A device of the character described, comprising an outer chase, vertical bars adjustably supported in the outer chase, horizontal bars between the vertical bars, fixed 60 notched extensions on the outer faces of the vertical bars adjacent one end of the latter, notched blocks on the outer faces of said vertical bars adjacent their other ends, turnbuckles connecting said blocks and exten-

sions, and stays connecting the notched extensions with the lower bar and the notched blocks with the upper bar, said vertical bars having longitudinal slots therein receiving the stays.

3. A device of the character described, 70 comprising an outer chase, vertical bars adjustably supported in the outer chase, horizontal bars between the vertical bars, fixed notched extensions on the outer faces of the vertical bars adjacent one end 75 of the latter, notched blocks on the outer faces of said vertical bars adjacent their other ends, turnbuckles connecting said blocks and extensions, stays connecting the notched extensions with the lower bar and 80 the notched blocks with the upper bar, said vertical bars having longitudinal slots therein receiving the stays, said horizontal bars having notched edges, and pins on the stays engaging the notched edges of the horizontal 85 bars and the notched members on the vertical bars.

4. A device of the character described, comprising an outer chase having beveled or rabbeted surfaces on its upper member, 90 and a rabbeted lower member, vertical bars having beveled or rabbeted upper ends and rabbeted lower ends engaging said faces of the outer chase members, one of said chase members having a series of notches 95 therein, a tongue on one end of one of the vertical bars engaging in any of said notches, horizontal bars connecting the vertical bars, and adjustable means carried by the vertical bars and adapted to adjust the 100 horizontal bars toward and away from each other.

5. A device of the character described, comprising an outer chase having beveled or rabbeted surfaces on its upper member, 105 and a rabbeted lower member, vertical bars having beveled or rabbeted upper ends and rabbeted lower ends engaging said faces of the outer chase members, one of said chase members having a series of notches therein, 110 a tongue on one end of one of the vertical bars engaging in any of said notches, horizontal bars connecting the vertical bars, adjustable means carried by the vertical bars and adapted to adjust the horizontal bars 115 toward and away from each other, and curved runners on the end members of the outer chase constituting ink roller carriers.

6. A device of the character described, comprising an outer chase, vertical bars 120 movably connected with the chase, horizontal bars between the vertical bars, said horizontal bars curved or sprung longitudinally, and devices at the ends of the horizontal bars securing them to the vertical 125 bars.

ERNEST KARL
